UNITED STATES PATENT OFFICE.

ANATOLE PANALLE AND SAM L. NEEDLE, OF WASHINGTON, DISTRICT OF COLUMBIA.

SAFETY DEVICE.

Application filed June 29, 1927. Serial No. 202,340.

Our present invention pertains to safety devices and it contemplates the provision of an extremely simple and inexpensive device through the medium of which a person practicing the invention may float in water without fear of sinking.

The invention further contemplates the provision of a safety device for the purpose above indicated that is self inflating and deflating.

The invention further contemplates the provision of a device that is at once adapted to be secured or attached to the person practicing the invention and is also adapted to be collapsed when removed from the body of the wearer.

The invention further contemplates the provision of a safety attachment that may be secured in a removable manner to a bathing suit and when so secured fear of casual collapse is eliminated due to the fact that when the attachment is properly arranged on the body of the wearer deflation of the device is impossible.

Other advantageous characteristics and features of our invention will be fully understood from the following description and claims when the same are read in connection with the drawings accompanying and forming part of this specification, in which:

Figure 1 is a perspective view of our novel safety device.

Figure 2 is a sectional view taken in the plane indicated by the line 2—2 of Figure 1 and looking in the direction of the arrows.

Figure 3 is a transverse sectional view taken in the plane indicated by the line 3—3 of Figure 1 and looking in the direction of the arrows.

Figure 4 is a perspective view of the device as collapsed.

Figure 5 is a sectional view of a portion of the device and showing the manner in which the ribs are secured in the walls of our improvement.

Similar numerals of reference designate corresponding parts in all the views of the drawings.

Our device is preferably formed of balloon cloth, although any water and air proof material may be used and although we have illustrated the device of the shape shown in Figure 1 it may be of any shape compatible with its purpose.

The device comprises a top wall 1 and a lower wall 2, and the said walls are ce-

mented or otherwise secured to each other to form the folded paper edge 3. The said walls are further folded and glued at their ends 4 and 5. Arranged in the end walls 6 and 5 if preferred are snap fasteners 6 through the medium of which the device may be secured to a bathing suit provided with complimentary fastening devices. At this point we would distinctly have it understood that no particular form of fastening means are to be considered a part of this application as in the future practice of this device any means may be used to secure our improvements to the body of the wearer.

Arranged to run cross-wise with respect to the length of our device and interiorly of the top wall 1 and lower wall 2 are spring bands 8, 9, 10, 11, 12, 13, 14, 15 and 16. These spring bands are of an extremely light material preferably of thin sheet steel and are adapted to hold the top wall and bottom wall away from each other. As clearly shown in Figure 2, for example the rib 10 illustrated is of a continuous piece of material and the said bands or ribs 10 are secured in the walls 1 and 2 by means of strips 17 and 18. The strips 17 are arranged interiorly of the walls 1 and 2 and bear on the upper surface of the bands or ribs. A similar strip 18 is cemented or otherwise secured to the strip 17 and bears against the under wall of the ribs as shown in Figure 2. These strips 17 and 18 are cemented to each other and the strip 17 in turn is cemented to the walls 1 and 2 and where they encounter the spring bands or ribs 9 to 16, one strip bears exteriorly of the ribs and the other on the under side of the ribs and at the contact point they are cemented to the ribs. This construction may be duplicated interiorly of the edges 3 of the device. It will be manifest that the strips 17 and 18 will when the device is collapsed accommodate themselves to permit positioning of the device to that shown in Figure 4. During the collapsing position the ends 3 will roll into the position between the ribs as indicated by 19 in Figure 4.

Secured in one end of the device is an air valve 7 and when the device is opened after the manner of an accordian air will rush into the interior of the device to inflate the same. The valve is turned so as to close the passage through the stem thereof and the de-

vice will therefore be retained in inflated condition. To deflate the device it is merely necessary to open the valve and push the walls 4 and 5 toward each other. Manifestly 5 blowing into the valve to inflate the device is not necessary.

Although we have illustrated our invention in the configuration shown we are not to be confined to any particular shape or 10 size of the device and the material used will be any material compatible with the purpose and the ribs or bands may be formed of any material and of any shape that may suggest itself in the future practice of the 15 invention.

The device, moreover, may be worn on the body with or without a bathing suit or with or without clothing and although its 20 primary use is for enabling or assisting a person to learn to swim it is also well adapted as a life preserver and of course straps or any other fastening means may be employed to secure the device to the body of the wearer.

26 What we claim:—

1. A safety device comprising a body por-

tion formed of two pieces of water and air tight material secured to each other, metallic ribs adapted to rest in the body portion, strips arranged interiorly of the body portion and extending longitudinally with respect thereto and other strips secured on the first strips in such a manner that the ribs are secured between the strips at the point of contact of the ribs with respect to the 30 strips.

2. A safety device comprising a body portion having an upper and lower wall secured to each other, a valve arranged in one of the walls, bendable ribs arranged interiorly of 40 the walls and means for securing the bendable ribs in the walls and comprising longitudinally arranged strips some of which are secured to the walls and the others of which are secured on the first named strips where- 45 by a loop is formed to engage a portion of the bendable ribs.

In testimony whereof we have hereunto set our hands.

ANATOLE PANALLE.
